UNITED STATES PATENT OFFICE

FRANK L. HETZEL, OF HERMOSA BEACH, CALIFORNIA

PNEUMATIC LOUD SPEAKER

Application filed September 26, 1930. Serial No. 484,608.

This invention relates to loud speakers of the pneumatic type which include in their construction an air valve to which vibrations are imparted.

5 The general object of the invention is to provide a pneumatic loud speaker of improved construction and having improved means for effecting the vibration of the air valve.

10 A further object of the invention is to improve the general construction of air valves of the grid type and to provide improved means for adjusting the grids relatively to each other.

15 A further object of the invention is to produce an air valve of simple construction and capable of receiving vibrations capable of producing sound, whether produced by a sound-translating device or through the agency of a record.

Further objects of the invention will appear hereinafter.

The invention consists in the novel parts and combination of parts to be described hereinafter, all of which contribute to produce an efficient pneumatic loud speaker.

20 A preferred embodiment of the invention is described in the following specification, while the broad scope of the invention is 30 pointed out in the appended claims.

In the drawings:

Figure 1 is a vertical section through the upper portion of the apparatus embodying my invention, certain parts being broken 35 away.

Figure 2 is a side elevation of the same apparatus upon a reduced scale, certain parts being broken away.

Figure 3 is an ideal horizontal section 40 through the apparatus taken about at the level of the line 3—3 of Figure 2 but upon an enlarged scale, certain parts being broken away.

Figure 4 is a horizontal section taken about 45 on the line 4—4 of Figure 2, and particularly illustrating the construction of the electrodynamic means for imparting vibrations to the air valve.

Figure 5 is a vertical section taken about on 50 the line 5—5 of Figure 2.

Figure 6 is a front elevation of the relatively movable grid of the air valve showing a portion of the fixed grid broken away.

Before describing the invention in detail, it should be stated that in the present specification I have described the apparatus as constructed so that the air valve is vibrated through an electromagnetic vibrating device, but it should be understood that in practice the air valve can be vibrated by any other means, for example, a phonograph record. So far as the air valve is concerned, it is merely necessary to impart the vibration corresponding to the sounds it is desired to reproduce in the loud speaker. My invention, however, concerns the electromagnetic means as well as the air valve and its connections to the horn of the loud speaker.

Referring more particularly to the parts, 1 represents an electromagnetic vibrating device which may have some of the features of construction of a magnetic speaker; that is to say, it may include a large permanent U-shaped magnet 2 between the forks of which laminated pole pieces 3 are mounted, and between these pole pieces a gap 4 is formed to receive an oscillator or armature 5 in the form of a bar of magnetic metal, said oscillator being preferably mounted on a flexible bridge or bridge bar 6. (See Fig. 4.) The 20 plates of the laminated pole pieces 3 are cut away in the usual manner to form projecting pole pieces or forks 7, thereby forming a relatively large gap 8 which receives the voice-coil 9 of the device. When the device is in use, this coil has its terminals 10 connected into the sound controlled circuit over which the electric impulses come that have been influenced or produced through the agency of 25 sounds.

The oscillator 5 is provided with a damper device in the form of a link 11 consisting of a thin plate which is attached to one end of the oscillator 5 and extends across to one side where it is secured to an adjustable anchor plate or anchor bar 12. This anchor bar is adjustable in a longitudinal direction to adjust the position of rest of the oscillator 5. According to my invention I provide 30 for dampening the vibrations of the oscillator 35 40 45 50 55 60 65 70 75 80 85 90 95 100

tor. For this purpose I extend the anchor bar upwardly and clamp it between two soft cushions or pads 13 of rubber or similar material. These pads 13 are clamped between the head 13a of a clamping bolt and an adjustable washer 13b on the threads of the clamping bolt. The upper end of the anchor bar is slotted to receive the clamping bolt.

By adjusting the bolt and washer it will be evident that the position of the anchor bar can be regulated as well as the degree of dampening.

The pneumatic apparatus of this device is preferably mounted above the electromagnetic mechanism as indicated in Figure 1 and preferably includes a frame 14 with an integral tubular sleeve 15 to one side of which the horn 16 of the loud speaker is attached. The mechanism also includes a sound box 17

20 in the form of a rectangular or box-like casting having an opening 18 at one side for the admission of compressed air. At another point the sound box is provided with an outlet opening 19 at which the air valve 20 is located. This air valve preferably consists of a relatively fixed grid 21 and a relatively movable grid 22. The grid 21 is rigidly secured on the face of the sound box, preferably by clamping it into position in the manner indicated in Figure 3. That is to say, this grid is in the form of a plate clamped between a tubular fitting 23 and the face of the sound box. If desired the grid 21 may be sweated to the forward wall of the box.

35 The sound box is preferably not rigidly supported, but is mounted so that it is capable of slight movements on a horizontal axis. For this purpose the sound box is preferably supported from its rear wall on a back leg 40 mounted on gudgeons 25 placed in upwardly projecting ears or brackets 26 that project up from the base plate of the frame 14.

The upper end of this back leg is provided with a slot as indicated at 27 which receives an adjusting stud 28 that projects from the rear wall of the sound box and receives a wing nut 29 for clamping the parts in any desired adjusted position. The air valve is 50 constructed with openings in the movable grid of larger size than those in the other grid.

The relatively fixed grid 21 has a plurality of substantially parallel outlet slots 30, and 55 similar slots 31, but of greater width, are formed in the relatively movable grid 22. This relatively movable grid 22 is constructed so that it will be light but with considerable rigidity. For this purpose I prefer to 60 construct it of duralumin and provide it with stiffening ribs 32 on its outer face lying between the slots. The slots 31 should be aligned midway between the slots 30 and the relatively movable grid normally lies flat 65 against the face of the fixed grid. The mov-

able grid is mounted so that it is capable of rocking toward or from the fixed grid, and in addition to this, means is provided for effecting a lateral adjustment of the grids with respect to each other. I prefer to accomplish this by mounting the movable grid so that it may be adjusted in a direction transverse to the direction of the slots. In this connection reference is had to Figures 1 and 5 in which the lower portion of the movable grid is indicated as provided with a downwardly projecting extension or arm 33.

There should be one more of the slots 30 than the slots 31. This appears to be important and the movable grid should be adjusted so that its slots 31 are exactly midway between the slots 30.

At its upper portion this extension or arm 33 is extended laterally to form a relatively large foot 34 which is attached to the under side of a flexible rocker or vibrating plate 35, the ends of this plate being received on flat seats 36 and provided with slots at 37 to receive clamping screws 38. The ends of the plate are in line with adjusting set screws 39 that screw into lugs 40 projecting down from the sound box (see Fig. 2). Evidently by loosening up the clamping screws 38 the adjusting screws 39 may be screwed in or out so as to effect a nice adjustment of the slots in the movable grid with respect to the slots of the fixed grid.

The flexible rocking plate 35 is mounted against fulcrum means on its upper side to enable it to rock, thereby enabling the movable grid 22 to approach or recede from the fixed grid or seat of the air valve. This means may be in the form of two pins 36a (see Fig. 5) that project down from the bottom of the sound box.

The lower end of the extension 33 carries a stylus 41 which may be clamped in place by a clamp screw 42. If desired, this stylus 41 may be made as an integral extension of the upper end of the oscillator 5. I prefer, however, to provide the upper end of the oscillator 5 with a stem 43 of reduced diameter surmounted by a head 44 from which the stylus 41 extends upwardly.

If desired, this stylus can be made as a separate part from the oscillator 5 and provided with a point at its lower end received in a small socket formed in the upper face of the head 44.

The sound box is preferably pressed downwardly toward its forward side by a flat spring 45 (see Fig. 1), which spring is anchored on a pivot screw 46 and passes through a guide slot 47 in an integral fin 48 projecting up from the upper side of the tubular sleeve 15. By swinging this spring 45 to one side, the sound box can be swung upward on the axis of the gudgeons 25 so as to give access to the air valve.

Between the connection 23 and the sleeve

15 a gap 49 should be formed to prevent metallic connection directly from the part 23 to the horn 16. This prevents vibration of the horn being imparted metallically to the 5 valve. However, this gap 49 is preferably closed by a pliable sleeve or band 50 of rubber or similar soft material that is not adapted to transmit vibrations.

10 The base plate of the bracket 14 has a slot 51 formed through it through which the upper end of the oscillator 5 extends.

15 The adjustment for the oscillator 5 may include an adjusting screw 52 (see Fig. 1), the head of which carries a collar 53 that is secured to the lower end of the anchor bar 12 referred to above. By loosening up on the thumb head 54 that clamps the dampers 13 against the anchor plate, this screw 52 may be adjusted up or down so as to tilt the 20 oscillator 5 on the longitudinal axis of the bridge plate 6. In this way suitable adjustments in this regard can be made. The damper cushions should be operated to cooperate with the adjusting screw 52 in affecting such adjustments.

25 The under side of the fitting or throat piece 23 may be provided with an opening or throat 55 through which the movable grid 22 can be put in place from below.

30 In the operation of the device, when electric impulses pass through the coil 9 they cause oscillation in a vertical plane of the oscillator 5, these oscillations correspond in period to the pulsations or impulses of the 35 current passing through the coil. In this way vibration is imparted to the movable grid 22 of the air valve corresponding to the different sounds. This opens the air valve more or less and permits the air under 40 pressure to escape through it into the horn.

The air takes up the vibration of the movable grid and the sound can be reproduced with an extraordinary amplification of its volume.

45 The compressed air I have employed gave satisfactory results at pressures between 7 and 25 pounds per square inch. If the air valve is to be operated by a phonograph record, a regular phonograph needle or stylus is 50 substituted for the stylus 41, its lower end being pointed and running in the record groove.

55 It should be noted that the pliable connection 50 cooperates with the spring 45 to permit free movement of the fitting 23 and sound box independent of the rigid horn sleeve 15.

60 It is understood that the embodiment of the invention described herein is only one of the many embodiments this invention may take, and I do not wish to be limited in the practice of the invention, nor in the claims, to the particular embodiment set forth.

What I claim is:

65 1. In a pneumatic loud speaker, the combination of an air valve with a relatively fixed

grid and a movable grid opposite the relatively fixed grid, an electromagnetic vibrator device having a voice coil and an oscillator mounted for vibration by the said coil and connected with the movable grid to oscillate 70 it toward and from the relatively fixed grid.

2. In a pneumatic loud speaker, the combination of a relatively fixed grid and a relatively movable grid, an electromagnetic vibrator device having a voice coil and an oscillator mounted for vibration by the said coil and connected with the relatively movable grid for vibrating the same, and means for effecting lateral adjustment of the grids with respect to each other. 75

3. In a pneumatic loud speaker, the combination of a relatively fixed grid with slots therein and a relatively movable grid with slots therein seating against the face of the fixed grid and with the slots of the relatively 80 movable grid out of line with the slots of the relatively fixed grid, means for supporting the relatively movable grid to rock toward or from the relatively fixed grid, an electromagnetic vibrator device having a voice coil, 85 and an oscillator, mounted for vibration by the said coil and connected with the relatively movable grid for vibrating the same.

4. In a pneumatic loud speaker, the combination of a relatively fixed slotted grid and a relatively movable slotted grid mounted to seat on the first-named grid, means for supporting the movable grid to enable the same to rock toward or from the fixed grid, an actuating arm carried by the movable grid, an electromagnetic vibrator device having a voice coil, and a vibrator mounted for vibration by the said coil and connected with the 90 said actuating arm for vibrating the movable grid. 100

5. In a pneumatic loud speaker, an air valve having a relatively fixed grid with outlet openings therein, a movable grid seating on the face of the fixed grid and having outlet openings therein of larger dimensions than the openings in the fixed grid and seating on the face of the fixed grid so that the openings of the movable grid are out of alignment with the openings of the fixed grid, and means for vibrating the movable grid. 110

6. An air valve constructed as described in claim 5 in which the outlet openings in the grids are in the form of substantially parallel slots with the slots of the relatively movable grid of greater width than the slots in the fixed grid and located precisely midway between them. 120

7. In a pneumatic loud speaker, the combination of an electromagnetic vibrator device having a voice coil, and an oscillator mounted for vibration by the said coil, a sound box with an air valve connected with the vibrator, and means for pressing the sound box toward the vibrator device. 125

8. In a pneumatic loud speaker, the com-

bination of an electromagnetic vibrator device having a voice coil and an oscillator mounted for vibration by the said coil, a sound box mounted so that it is capable of 5 moving on an axis, an air valve with the sound box connected with the oscillator, and means for pressing the sound box toward the vibrator device.

9. In a pneumatic loud speaker, the combination of a relatively fixed grid having substantially parallel outlet slots for the air, a relatively movable grid with substantially parallel slots and seating on the first-named grid with the slots of one grid out of alignment with the slots of the other grid, and means for effecting a relative adjustment of 15 said grids laterally with respect to the direction of the slots.

10. In a pneumatic loud speaker, the combination of a relatively fixed grid having substantially parallel slots, a relatively movable grid seating on the same and having substantially parallel slots out of alignment, but substantially parallel with the first-named 25 slots, a flexible rocking plate attached to the relatively movable grid, an actuating arm attached to the flexible rocking plate, and means for adjusting the rocking plate in a direction at right angles to the direction in 30 which the slots extend.

11. In a pneumatic loud speaker, the combination of a relatively fixed grid with substantially parallel slots, a relatively movable grid with substantially parallel slots seating 35 on the face of the fixed grid with the slots of one grid out of alignment with the slots of the other grid, a flexible rocker plate with means for adjusting the same in a transverse direction with respect to the direction of the 40 slots, an actuating arm having a foot rigidly secured to the rocker plate and relatively fixed fulcrum means engaging the rocker plate adjacent the foot of the actuating arm.

12. In a pneumatic loud speaker, the combination of an air valve, an electromagnetic vibrator device having a voice coil, an oscillator mounted for vibration by the said coil and connected with the air valve for vibrating 45 the same, and cushion means distinct from the valve for dampening the vibration 50 of the oscillator.

13. In a pneumatic loud speaker, the combination of an air valve, an electromagnetic vibrator device having a voice coil, an oscillator mounted for vibration by the said coil and connected with the air valve for vibrating 55 the same, a bar connected with the oscillator, and damper means connected with the bar and having cushion means for clamping 60 the damped part on both sides.

14. In a pneumatic loud speaker, the combination of an air valve, an electromagnetic vibrator device having a voice coil, an oscillator mounted for vibration by the said coil and connected with the air valve for vibrat- 65

ing the same, a damper bar attached to the oscillator, an adjusting bar connected with the last named bar with means for nicely adjusting the same to regulate the position of the oscillator, and cushion means for clamping 70 the adjusting bar on both sides.

15. In a pneumatic loud speaker, the combination of an air valve, an electromagnetic vibrator device having a voice coil, an oscillator mounted for vibration by the said coil 75 and connected with the air valve for vibrating the same, a damper bar attached to the oscillator, an adjusting bar connected with the last named bar with means for nicely adjusting the same to regulate the position of the oscillator, and cushion means for clamping 80 the adjusting bar on both sides, said cushion means comprising a pair of cushions with means for adjusting the same for clamping the adjusting bar in its different adjusted 85 positions.

16. In a pneumatic loud speaker, the combination of an electromagnetic vibrator device having a voice coil, an oscillator mounted for vibration by the said coil, a sound box 90 with an air valve connected with the vibrator, means for pressing the sound box toward the vibrator device, and a horn having a pliable sleeve connecting the same with the sound box. 95
